VANITY BOX

Robert L. McKnight, Watertown, Conn., assignor
to Scovill Manufacturing Company, Waterbury,
Conn., a corporation of Connecticut

Application March 1, 1943, Serial No. 477,510

1 Claim. (Cl. 220—55)

This invention relates to receptacles and particularly to a vanity box that is designed to be made from long strips of molding-like material.

This invention is directed to improvements in a vanity box construction disclosed in the Le Roy P. Root patent application, Serial No. 476,582, filed Feb. 20, 1943, and which improvements relate particularly to the means for frictionally holding the cover in closed position relative to the body.

In a vanity box made according to Root's construction where preference is given to wooden materials, it has been found in actual practise that considerable clearance has to be allowed between the cover and the body so as to compensate for manufacturing tolerances and the factor of expansion and contraction that results in this material or the tacky effect that might result from the finishes used upon the box. To overcome such conditions that may result from the above factors and still provide for a frictional fit sufficient to hold the cover in closed position, the improvements in my invention resides particularly in the use of suitable frictional elements carried in the beaded end of the cover opposite from its hinging end, which elements are allowed to project beyond the transverse edges of the cover a sufficient distance to have firm frictional engagement with the adjacent walls of the body member. More specifically the friction elements are made from compact cylindrical felt wads forced into restricted sockets drilled into the transverse ends of the cover bead.

The full nature of this invention along with other objects and various advantages thereof will be more apparent from a consideration of the following description when read in connection with the accompanying drawing in which—

Fig. 1 represents a perspective view of the vanity box construction showing the cover in an opened position.

Fig. 2 is a plan view of the vanity box with the cover in a closed position, and

Fig. 3 is an enlarged sectional view drawn along the line 3—3 of Fig. 2 showing in detail the frictional means.

Referring now to the drawing in which the reference numerals designate like parts throughout the several views, numeral 10 indicates generally the body member and numeral 11 the cover member. As pointed out in the Root application, referred to above, the body and cover members are so designed as to be made preferably from wooden material that can be readily fabricated in long strips of molding material of gen-

eral U-shape in cross-section. In cutting the body from such a strip of molding material there will result two opposed upstanding side walls 13, whereas the other ends of the box will be open. Within the upper face of the base of the body there is provided a relatively large recess 14 into which powder may be disposed in accordance with the Root teaching.

The cover member 11 likewise is adapted to be transversely cut from long strips of molding material having two parallelling beaded edges 15 and 16 which become the ends of the cover member parallel to the longitudinal axis thereof. To form a compartment within the box when the cover is closed, the cover member is assembled in an inverted position, i. e., with the beads 15 and 16 in a dependent position, to the body member 10 with its axis normal to the longitudinal axis of the body member and in between the body side walls 13. One of the beaded edges 15 of the cover member which for convenience's sake will be called the hinging bead is pivotally engaged to the ends of the body side walls 13 through the medium of wooden pivot pins 17 driven into suitable recesses formed in from opposite ends thereof and have rotatable engagement in complementary aligned bearing openings 18 in the body side walls 13.

As pointed out in the objects of the invention, in order to preclude the cover from sticking or binding in between the side walls of the body when in closed position, a considerable amount of tolerances is allowed between the cover edges and side walls 13, therefore making it necessary to provide for means to hold the cover in closed position that will not be subject to the faults heretofore pointed out. To this end I provide a frictional means between the cover and body that takes effect only upon the complete closing of the cover member. This is accomplished by providing sockets 19 in the opposite ends of the front beaded edge 16 of the cover member and into which is forcibly assembled a cylindrical felt wad 20 of relatively firm consistency and of a length to project beyond the cut or transverse edges of the cover a distance sufficient to have a relatively firm frictional engagement with the adjacent surface of the body side walls 13 in a manner such as shown in Fig. 3. The felt wads are cut transversely from long cylindrical firmly compressed felt strips which thus provide for innumerable fibre ends that resiliently bear against the adjacent flat surface of the body flanges which preferably are left in a smooth finished state. The frictional effect produced by this con-

struction is sufficient to maintain the cover in closed position yet free enough to allow the operator to open the cover without having to exert an extreme amount of force in hinging the cover relative to the body.

To facilitate the opening of the cover there is provided an arcuate cut-out or thumb opening 21 in the front edge of the body that allows ample room for the operator to wedge his thumb underneath the front beaded edge 16 of the cover member and permit a sufficient thumb purchase thereagainst.

While the form of the invention herewith shown and described embraces a preferred embodiment of the same, it is to be understood that the construction may be varied as to mechanical details without departing from the spirit of the invention and the scope of what is claimed.

I claim:

In a vanity box of the character described comprising a body member having end flanges and

5 a cover member having an end hingedly connected to said flanges and entirely confined between said flanges when in a closed position, the opposite end of said cover member having sockets provided in each of its transverse edges, and compact cylindrical felt wads of a normal diameter slightly greater than said socket and disposed in said sockets under force of pressure to completely fill said sockets with one end of said wads firmly seated against the base of their respective sockets as a stop and the opposite end projecting beyond their respective cover edges a distance 10 to have frictional engagement with the adjacent smooth wall surface of said flanges, the degree 15 of frictional effect between the wad ends and the adjacent flange wall surfaces being uniform for both the closing and opening operations of said cover member when moving within the area of said flanges.

ROBERT L. McKNIGHT.
